CIRCUIT INTERRUPTER EMPLOYING MEANS FOR CONTROLLING METALLIC VAPOR EMISSION

Eugene W. Boehne, Wellesley Hills, Mass., assignor to Allis-Chalmers Manufacturing Company, Milwaukee, Wis.

Application April 9, 1957, Serial No. 651,635

16 Claims. (Cl. 200—147)

This invention relates to electric circuit interrupting devices, and more particularly to air circuit breakers of the magnetic blowout type.

It has been known for some time that arc vapor is one of the worst enemies in the performance of alternating or direct current circuit breakers. Vaporized metal in the arc stream tends to maintain and stabilize the arc thus hindering its interruption. In view of the fact that the metallic content of the arc stream depends principally upon metal vapors or particles derived from the arc runners it is important that the ends of the arc in contact with the arc runners be kept moving continuously in order to avoid heat concentrations and the consequent high vaporizing action. Inasmuch as arcs effect a vaporizing action of the materials used in the construction of an arc extinguishing device and since such vaporization tends to cause restriking of the arc at the exhaust end of the arc chute it is desirable to not only control the amount of metallic vapors but also its movement through the arc chute structure.

In accordance with the invention claimed, a new and improved compact circuit breaker structure is provided comprising a pair of relatively movable contacts, means for drawing an arc between said contacts, and an arc chute for receiving the arc at one end thereof and exhausting the arc products at the other end. The chute comprises a plurality of spaced insulating plates arranged to extend longitudinally of the axis of the chute at the arc receiving end thereof and a pair of chimney vents arranged longitudinally of the axis of the chute, one adjacent to each end of said barrier plates. A magnetic coil is arranged adjacent to the contacts for driving the arc into the chute. In order to expedite the movement of the arc into the arc chute a pair of arc runners are provided one arranged adjacent each of the contacts for providing a conductive path for the terminals of the arc from the contacts into the chimney vents. The arc runners are wrapped around at least a part of the coil and extend upstream therefrom to a position within the entrance ends of the chimney vents.

It is, therefore, one object of the present invention to provide a new and improved arc interrupting device.

Another object of this invention is to provide a new and improved arc interrupting device in which the vaporizing action of the arc on the arc runners of the device is minimized.

A further object of this invention is to provide a new and improved arc interrupting device in which the arc vapors are confined and directed in a predetermined

2

manner through the arc chute to assist in the extinction of the arc.

A still further object of this invention is to provide a new and improved circuit breaker structure in which the terminals of the arc are oscillated back and forth along the arc runners during an arc interrupting action, thus minimizing the generation of metallic ions.

A still further object of this invention is to provide an improved arc runner of a predetermined configuration for minimizing metallic vaporization therefrom.

Objects and advantages other than those set forth will be apparent from the following description when read in connection with the accompanying drawings, in which:

Fig. 1 is a view in vertical cross section of a magnetic blowout type of circuit breaker employing the present invention;

Fig. 2 is a cross sectional view through the contact structure of Fig. 1 taken along the line II—II;

Fig. 3 is a partial view in vertical cross section of a modification of the arc chute structure of the magnetic blowout type of circuit breaker illustrated in Fig. 1;

Fig. 4 is a plan view of the structure illustrated in Fig. 3;

Fig. 5 is a cross sectional view through the arc chute structure of Fig. 3 taken along the line V—V; and

Fig. 6 is a partial plan view of a modification of the splitter plate and chimney vent structure shown in Figs. 1—5.

Referring more particularly to the drawings by characters of reference, Fig. 1 illustrates a magnetic blowout type of circuit breaker employing an arc chute into which the arc is forced by the magnetic blowout field and extinguished. The power circuit to be interrupted includes relatively movable contacts between

35 which the arc is formed when the contacts separate at the entrance to the arc chute. Specifically, the contacts comprise a fixed contact structure 11 and a coacting movable contact structure 12. The fixed contact structure is electrically connected to a lead in conductor stud 30 defining one terminal of the breaker, and the movable contact structure 12 comprising a pivoted switch arm having an arcing contact mounted at one end thereof is electrically connected to a conductor stud 15 defining the other breaker terminal. The pivoted contact structure 12 is suitably operated between open and closed circuit position by an operating rod 16 that is connected through a crank 17 to a solenoid or other operating means 18.

Fig. 1 illustrates the movable contact structure 12 in contact open position, the coacting main and arcing contacts 20 and 22, respectively, of the movable contact structure 12 being spaced apart from corresponding main and arcing contacts 23 and 25, respectively, of the fixed contact structure 11. A pair of lugs 21 (one of which is shown in Fig. 1) are integrated with arcing contact 22

and extend from opposite sides of a web portion of arcing contact 22. Lugs 21 together with the web portion of the arcing contact 22 form an engaging surface which coacts with that of a block of insulating material 24 on the stationary contact structure 11 to limit overtravel of the movable contact structure 12 in the closing direction. In breaker closed position the stationary arcing contact 25 is shunted by stationary main contact 23. Opening of the breaker by the clockwise rota-

tion of the breaker movable contact structure 12 causes in the sequence named separation of the main current carrying contacts 20, 23 and the arcing contacts 22, 25. The power arc is formed at the entrance of an arc chute 26.

Arc chute 26 is illustrated as being provided with magnetic blowout means comprising blowout coils 28 and 29 arranged so as to cause the arc formed between the contacts 22 and 25 to be blown by the magnetic field into arc chute 26. Blowout coil 28 is connected at one end thereof to a conductive arc runner 30 and at the other end thereof immediately adjacent main contact 23. Blowout coil 29 is connected at one end thereof to a conductive arc runner 31 and at the other end thereof to a lower terminal extension 32 through a conductive bar 27.

Upon separation of the arcing contacts 22 and 25 in a circuit interrupting action the arc terminal is transferred from stationary arcing contact 25 to arc runner 30, thereby inserting blowout coil 28 in the arcing circuit traced from the point of connection of blowout coil 28 on the upper terminal block immediately adjacent main contact 23 through blowout coil 28 to arc runner 30, through the arc to movable arcing contact 22. As the arc, now established between arc runner 30 and the movable arcing contact 22, is attenuated by the clockwise rotation of contact structure 12, the arc envelops the lowermost portion of arc runner 31 thereby transferring the arc terminal from arcing contact 22 to arc runner 31 and inserting blowout coil 29 in the arcing circuit. The arcing circuit is now completed through the bar 27 which connects the blowout coil 29 with the lower terminal extension 32.

Referring more particularly to the movable contact structure 12 of one phase of a three phase circuit, as shown in Figs. 1 and 2 of the drawings the switch arm comprises a pair of spaced plates 35 (one of which is shown in Fig. 1) mounted on a pivot bolt 36. The spaced plates 35 are also interconnected by a pin 37 which serves to connect the switch arm to the operating rod 16. Secured to the plates 35 and mounted on bolt 36 with the spaced plates 35 are a pair of spaced plates 38. Plates 38 extend generally parallel along the inside surfaces of plates 35 and are joined to plates 35 by any suitable means such as rivets 40. Plates 38 are joined together at their outer extremity by the contact body or head forming the current carrying contact 20 and the arcing contact 22.

Arranged between the spaced plates 35 and 38 is a hollow fluid conducting stationary bearing 39 for the reciprocating switch arm or movable contact structure 12. This bearing may be made of any suitable material sufficiently strong to stand the shock of circuit breaker operations such as cast bronze.

Bearing 39, more particularly, is arranged between conducting extensions 32 on bolt 36. Spaced plate combinations 35, 38 are yieldingly biased toward each other and against the opposite sides of bearing 39 by any suitable means which, for example, may be spring washers 33 secured to bolt 36 by a nut 34. Washers 33 are held in stressed condition against the sides of spaced members 35 by bolt 36 and nut 34, thus providing high contact pressure. Conducting ring inserts 41 are provided between plates 38 and conducting extensions 32 to provide a line contact between the stationary and movable parts of this hinge connection. Bolt 36 which passes through suitable openings provided in spaced members 35, 38, extensions 32 and bearing 39, is provided with a closely fitting collar or shield 42 which serves to form a substantially fluid tight connection between the hollow opening in bearing 39 and the bolt 36.

The arcing contact structure and the arc chute of the circuit breaker structure are mounted on a supporting structure comprising a fabricated vehicular base structure 45. Mounted on base structure 45 is the circuit breaker operator 18 which may be a solenoid, pneumatic,

or a pneuma-oscillated hydraulic type of circuit breaker movable contact actuating means. A pair of dual purpose substantially vertical or diagonal tubular members 46 (one of which is shown in Fig. 1) are provided on base structure 45. Members 46 are connected to a horizontally arranged manifold 49 which supports a pair of horizontal cross bracing means 47 (only one of which is shown in Fig. 1). The circuit breaker elements comprising the movable contact mechanism of the circuit breaker and the arc chute are mounted on the horizontal cross bracing means 47 and the manifold 49. Members 46 in addition to supporting the circuit breaker, further collect and distribute to a zone of arc initiation fluid under pressure from a source of fluid under pressure such as a suitable pneumatic means 48 used for aiding in cooling and extinguishing an arc drawn by the circuit breaker elements between the arcing contacts.

This pneumatic means comprises an air pump comprising a cylinder 50 mounted on base structure 45 and a piston 51 movable in cylinder 50. Piston 51 is biased in contact opening direction by an operating spring 59 which is the means for opening the circuit breaker. The pneumatic means 48 serves a plurality of functions, namely, it is the motor actuating means for opening the contacts of the circuit breaker, it acts as an air pump to force air through the bearing 39 and nozzle 58 to aid in cooling and extinguishing the arc, and it acts as a shock absorber to retard the movement of the switch arm near the end of its opening stroke to reduce the impact of the movable contact structure 12 on the fixed structure of the circuit breaker. The solenoid operating means 18 through crank 17 returns piston 51 to its contact closed position after a circuit breaker opening operation and compresses spring 59 so it is capable of again opening the circuit breaker contacts. Any suitable means such as pipe connections 52 may be used for connecting the substantially vertically arranged tubular members 46 to the source of fluid under pressure, namely cylinders 50.

Manifold 49 is connected to the bearing 39 of each switch arm of each phase of the three phase circuit breaker through insulating tubular members 54. Bearing 39 comprising a hollow cylindrical member is provided with an outlet 55 (more clearly shown in Fig. 2). A slip ring 56 having attached thereto a tubular member 57 of high dielectric and flashover strength which terminates at its outer end in a nozzle 58 arranged adjacent the breaker elements in the zone of arc initiation is mounted around trunnion 39. Tubular member 57 is attached to the switch arm for movement therewith. As shown in Fig. 1, tubular member 57 is generally arranged parallel with the switch arm in a predetermined relationship with the contacts 20 and 22. Slip ring 56 is arranged to provide a passageway for air under pressure from cylinder 50 through tubular member 46, manifold 49, tubular member 54, bearing 39, tubular member 57, and nozzle 58 to the zone of arc initiation. Tubular member 57 and nozzle 58 are secured to spaced plates 38 so that slip ring 56 and nozzle 58 move concurrently with plates 38 upon actuation of the arcing contacts to circuit open or circuit closed position.

For the purpose of interrupting either low or high current arcs the switch arm or movable contact structure 12 is connected to piston 51 through operating rod 16, crank 17 and a piston rod 60. Upon the movement of contact structure 12 from closed to open circuit position under the action of springs 59, piston 51 is actuated and moved from the top of cylinder 50 to the bottom of cylinder 50. This movement of piston 51 causes air in cylinder 50 under piston 51 to flow through pipe connections 52, tubular member 46, manifold 49, tubular member 54, bearing 39, tubular member 57 and nozzle 58 to the zone of arc initiation. This blast of air under pressure cools the arc and drives it into the arc chute 26 for rapid arc extinguishing action.

In accordance with the invention claimed arc chute 26

comprises a first group of slotted spaced insulating plates 62 arranged to extend longitudinally of the axis of the chute and transversely to the arc at the arc receiving end thereof, second and third groups of spaced insulating splitter plates 63 and 64 arranged to extend longitudinally of the axis of the chute and substantially longitudinally of the arc with one of the second and third groups of plates being arranged at each end of the first group, and a pair of chimney vents 65 and 66 arranged longitudinally of the axis of the chute one adjacent each of the second and third groups of splitter plates at the outer edges thereof.

The insulating barrier plates 62 of the first group may be arranged in a combination having a plurality of types of barrier plates having different geometrical configurations. Slots 67 of barrier plates 62 are aligned at their upstream ends adjacent the zone of arc initiation to form an arc passage. As well known in the art the slots may be arranged in staggered relation at their downstream ends. This out of registry or staggered relationship of the slots causes the formation of a zigzag shaped arc path. Barrier plates 62 may be provided in some applications of this invention with a plurality of apertures or perforations which may be arranged to extend from the downstream ends of slots 67 toward the exhaust end of the arc chute.

The second and third groups of splitter plates 63 and 64 each comprise four splitter plates arranged to extend transversely to the side walls of the chimney vents 65 and 66. As shown in Figs. 1, 3 and 4 the splitter plates are arranged in a vertical manner such as to receive the arc vertically from the arc runner. The magnetic forces due to the field of the blowout coils as well as the natural loop of the arc current will drive the arc into the splitter plate areas. The splitter plate groups may have any number of plates some or all of which may be provided with a plurality of apertures or perforations 80 extending therethrough for equalizing the gas pressure within the various channels provided by the splitter plates themselves. These channels are sometimes known as the interplate spacings.

The chimney vents 65 and 66 are arranged at the ends or sides of the groups of splitter plates 63 and 64 and above the arc runners 30 and 31. These vents direct the arc products and gases created by the arc terminals moving along the arc runners out of the arc chute to atmosphere. The extent of the ionization of the gas and the volume of the arc products produced by the action of the arc on the arc runners vary directly with the amount of current being interrupted and the voltage characteristics of the interrupter. It is recognized that the arc products may interfere with the action of the barrier plate stack. Consequently chimney vents 65 and 66 are separated from the barrier plate and splitter plate stacks and discharge the gases and arc products from the arc runners directly to atmosphere without going through these stacks.

As noted from the drawings the arc runners direct the terminals of the arc into the chimney vents. These arc runners are arranged to wrap around at least a part of the coil or coils of magnetic means 28, 29 and each extends upstream therefrom to a position within or adjacent the entrance end of a different one of the chimney vents 65 and 66. If so desired the arc runners may be wrapped directly around the blowout coil or coils or merely positioned adjacent thereto and then extend therefrom upstream to the floor or base 70 of the chimney vents in a smooth, gentle curve. In Figs. 1 and 3 the arc runners are shown as extending downstream from the contacts, around at least a part of the magnetic means, upstream a predetermined distance and into the entrance ends of the chimney vents. In passing into the entrance ends of the chimney vents the arc runners extend upstream a predetermined distance across the arc receiving end of the splitter plates and to a horizontal position in the chimney vents. The base or chimney portion of the

arc runners is usually horizontal to the circuit breaker structure and extends into chimney vents 65 and 66 through apertures 71 and 72, respectively. As shown in Fig. 3 the wall surface 73 of chimney vent 65 or the same wall surface of chimney vent 66 may be provided with a plurality of apertures 74 adjacent the apertures or openings 71 and 72 for equalizing the gas pressure between the chimney vent and the adjacent stack of splitter plates.

Fig. 6 illustrates a modification of the splitter plate assemblies shown in Figs. 1-5 wherein the plates 75 of the stack are less in width than plates 76 and extend out from the wall 73 of the chimney vent 65 a shorter distance than do the plates 76.

When the arcing contacts 11 and 12 are separated to draw an arc, the arc terminals move from the contacts to approximately points 77 on arc runners 30 and 31 and continue to run over arc runners 30 and 31 until the terminals reach approximately the vent openings 71 and 72 in the chimney vents 65 and 66. Up to this point in the interrupting action the arc column usually precedes the point of contact of the arc with the arc runner. As the arc terminals pass openings 71 and 72 and move into the chimney vents the arc column will trail the arc terminals along the arc runners. The arc terminals after reaching openings 71 and 72 in chimney vent walls 73 will proceed rapidly into the base of the chimney vents due to the large magnetic forces acting on the current load and aided by the internal pressure within the arcing chamber. At this point in the interrupting cycle of the arc the voltage drop across the extending arc column will increase and the arc will restrike across the arc runner between points closer to the crest of the arc runner curve, namely, near points 78. The arc terminals will then proceed along the arc runners in the manner heretofore explained. This process of arc column extension and arc terminal movement along the arc runners will be repeated numerous times until a current zero is forced or reached at which time interruption of the arc will take place. The pressures inside of the main arc chamber will act to drive the arc gases and arc products up the chimney vents and these gases and arc products will be vented externally of the arc chute structure and separate from the exhaust of the main arc column.

The splitter plates of groups 63 and 64 are arranged in a vertical manner so as to receive the arc running across the arc runner vertically therefrom. The magnetic forces due to the field of the blowout coil, as well as the natural loop of the arc current drives the arc into the splitter plate areas. The arc by traveling in a vertical manner at both sides of the arc chute develops its largest voltage drop. In the construction of the arc chute shown in the drawings the blowout coils 28 and 29 are arranged immediately below the barrier plates. In this manner the barrier plates, blowout coils and the current loop force the arc terminals into the chimney vents and the arc adjacent thereto into the splitter plate areas to aid arc extinction.

The separate venting chimneys and arc runner arrangement as disclosed above are not unalterably associated with the arc chute structure shown. New and other arc chute modifications are recognized as being possible with the venting chimneys as disclosed. In a similar manner other operating mechanisms are not to be excluded as being within the scope of this invention.

Further, this new and improved circuit breaker structure is adaptable for both alternating and direct current interrupting devices.

Although but a few embodiments of the present invention have been illustrated and described, it will be apparent to those skilled in the art that various changes and modifications may be made therein without departing from the spirit of the invention or from the scope of the appended claims.

What is claimed is:

1. An electric circuit interrupter comprising a pair of

spaced insulating plates arranged to extend longitudinally of the axis of said chute and transversely to the arc at the arc receiving end thereof, a second group of spaced insulating splitter plates arranged to extend longitudinally of the axis of said chute and substantially longitudinally of the arc at one end of said first group, and a chimney vent arranged longitudinally of the axis of said chute adjacent said second group at the outer edge thereof, a magnetic coil arranged adjacent said contacts for driving the arc into said chute, and an arc runner arranged adjacent one of said contacts for providing a conductive path for a terminal of the arc from said one of said contacts into said vent, said arc runner extending downstream from one of said contacts, around at least a part of said coil, upstream a predetermined distance across the arc receiving end of said second group and to a horizontal position within the entrance end of said vent.

11. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, second and third groups of spaced insulating splitter plates arranged to extend longitudinally of the axis of said chute and substantially longitudinally of the arc, one of said second and third groups being arranged at each end of said first group, and a pair of chimney vents arranged longitudinally of the axis of said chute one adjacent each of said second and third groups at the outer edges thereof, and a pair of spaced arc runners one being arranged adjacent each of said contacts for providing a conductive path for the terminal of the arc from said contacts across the arc receiving ends of said second and third groups and into each of said vents.

12. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, second and third groups of spaced insulating splitter plates arranged to extend longitudinally of the axis of said chute and substantially longitudinally of the arc, one of said second and third groups being arranged at each end of said first group, and a pair of chimney vents arranged longitudinally of the axis of said chute one adjacent each of said second and third groups at the outer edges thereof, a magnetic means arranged adjacent said contacts for driving the arc into said chute, and a pair of spaced arc runners one being arranged adjacent each of said contacts for providing a conductive path for the terminals of the arc from said contacts into each of said vents, said arc runners being wrapped around at least a part of said magnetic means and each extending upstream therefrom adjacent the arc receiving end of said second and third groups to a position within the entrance end of said vents.

13. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, a second group of spaced insulating splitter plates arranged to extend longitudinally of the axis of said chute and substantially longitudinally of the arc at one end of said first group, at least some of said splitter plates being provided with a plurality of apertures for equalizing the fluid pressure within the interplate spacings, a chimney vent arranged longitudinally of

the axis of said chute adjacent said second group at the outer edge thereof, and an arc runner arranged adjacent one of said contacts for providing a conductive path for a terminal of the arc from said one of said contacts across the arc receiving end of said second group and into said vent.

14. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, a second group of spaced insulating splitter plates arranged to extend longitudinally of the axis of said chute and substantially longitudinally of the arc at one end of said first group, a chimney vent defined by a wall surface arranged longitudinally of the axis of said chute adjacent said second group at the outer edge thereof, a magnetic coil arranged adjacent said contacts for driving the arc into said chute, and an arc runner arranged adjacent one of said contacts for providing a conductive path for a terminal of the arc from said one of said contacts into said vent, said arc runner being wrapped around at least a part of said coil and extending upstream therefrom adjacent the arc receiving end of said second group to a position within the entrance end of said vent, said wall surface being provided with a plurality of apertures arranged adjacent the arc receiving end of said vent for equalizing the gas pressure between said vent and said second group of splitter plates.

15. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, a second group of spaced insulating splitter plates arranged to extend longitudinally of the axis of said chute and substantially longitudinally of the arc at one end of said first group, at least some of said splitter plates being provided with a plurality of apertures for equalizing the fluid pressure within the interplate spacings, a chimney vent defined by a wall surface arranged longitudinally of the axis of said chute adjacent said second group at the outer edge thereof, a magnetic coil arranged adjacent said contacts for driving the arc into said chute, and an arc runner arranged adjacent one of said contacts for providing a conductive path for a terminal of the arc from said one of said contacts into said vent, said arc runner being wrapped around at least a part of said coil and extending upstream therefrom adjacent the arc receiving end of said second group to a position within the entrance end of said vent.

16. An electric circuit interrupter comprising a pair of relatively movable contacts, means for drawing an arc between said contacts, an arc chute for receiving the arc at one end thereof and exhausting the arc products at the other end, said chute comprising a first group of spaced insulating plates arranged to extend longitudinally of the axis of said chute and transversely to the arc at the arc receiving end thereof, a second group of spaced insulating splitter plates arranged to extend longitudinally of the axis of said chute and substantially longitudinally of the arc at one end of said first group, at least some of said splitter plates being provided with a plurality of apertures for equalizing the fluid pressure within the interplate spacings, a chimney vent defined by a wall surface arranged longitudinally of the axis of said chute adjacent said second group at the outer edge thereof, a magnetic coil arranged adjacent said contacts for driving the arc into said chute, and an arc runner arranged adjacent one of said contacts for providing a conductive path for

a terminal of the arc from said one of said contacts into said vent, said arc runner extending downstream from one of said contacts, around at least a part of said coil, upstream a predetermined distance across the arc receiving end of said second group and to a horizontal position within the entrance end of said vent, said wall surface being provided with a plurality of apertures arranged adjacent the arc receiving end of said vent for equalizing the gas pressure between said vent and said second group of splitter plates.
